United States Patent Office

Des. 177,688
Patented May 15, 1956

177,688

TABLE ORNAMENT OR SIMILAR ARTICLE

Andrew A. Mina, Point Pleasant, N. J.

Application November 30, 1954, Serial No. 33,333

Term of patent 7 years

(Cl. D29—28)

FIG. 1.

FIG. 2

Fig. 1 is a front perspective view of a table ornament or similar article;

Fig. 2 is a side elevation of the ornament shown in Fig. 1.

The dominant features of my design reside in those portions shown in full lines.

I claim:

The ornamental design for a table ornament or similar article as shown and described.
